UNITED STATES PATENT OFFICE.

HANS HARDEGGER, OF ARBON, SWITZERLAND, ASSIGNOR TO WILHELM STELLMACHER,
OF ARBON, SWITZERLAND.

EMBROIDERY-FRAME FOR EMBROIDERY-MACHINES.

1,204,434.

Specification of Letters Patent.

Patented Nov. 14, 1916.

Application filed January 23, 1913. Serial No. 743,793.

To all whom it may concern:

Be it known that I, HANS HARDEGGER, a citizen of Switzerland, residing at Arbon, Switzerland, have invented a new Embroidery-Frame for Embroidery-Machines, of which the following is a specification.

My invention relates to improvements in embroidery machines.

In known embroidery machines the frames are rectangular in form and have various disadvantages due to the weight of the frame which is too heavy and consequently the machine work is poor. At the slightest increase in the usual number of movements of the machine, vibrations of the frame occur by which the goods suffer. Furthermore the frames can only be built of a limited length, for example ten yards, for with a longer construction injurious vibrations cannot be avoided.

The object of the present invention is to overcome these disadvantages and the invention consists in providing as a substitute for the rectangular frame, a series of fabric roller supports, which are capable of being moved laterally and longitudinally either at different times or simultaneously.

In the accompanying drawings—Figure 1 is a front elevation of the left hand end portion of an embroidery machine embodying my invention. Fig. 2 is an elevation of the right hand end portion, and, Fig. 3 is an enlarged detail transverse vertical section of the lower portion of the frame.

The machine frame comprises vertical end members 1 and 2 connected together by horizontal transverse members 3, 4. A plurality of horizontal fabric rollers 5, 6, 7, and 8 of well known form are carried by a series of supporting members 9, 10 and 11, which are movable longitudinally and transversely of the members 3, 4, on which they are mounted.

The supporting members are provided with flanges 12 and 13 formed near their upper and lower ends 14 and 15, the flanges being engaged by forked members 16 and 17, respectively, which are formed as double bell-crank levers and are preferably provided with anti-friction rollers 18, in their free or forked ends so as to provide a sliding connection between the supporting members and the levers.

The forked members or double bell-crank levers are pivoted in brackets 19 mounted on the transverse members 3, 4, and the levers at the upper and lower part of the machine are connected together in series by pull-rods 20, 21, and 23, 24 respectively and both series of levers are connected together by a rod 22, which carries a weight 25, Fig. 2, to counterbalance the weight of the fabric rollers.

The supporting members 9, 10 and 11 are connected to tie-rods 26 and 27 by means of anti-friction rollers 28 which engage the members and permit a free movement of the latter transversely of said tie-rods. These tie-rods 26, 27 are connected to operating rods 29, 30 respectively by means of two-armed levers 32 pivoted on the end frames 1 and 2. The right-hand levers 32 are provided with lever arms 33 which are connected together by a rod 31.

If the embroidery frame is to be moved upward, it suffices to move the left supporting member 9 in an upward direction. This upward movement of said member moves, through the medium of the levers 16 and 17, the pull rod 21 toward the left and the pull rod 23, toward the right, said rods causing a parallel movement of all the levers 16 and 17 and an upward movement of supporting members 10 and 11.

If the supporting member 9 is moved to the right the pull rod 26 will also move to the right and, through the medium of levers 32, the rod 29 will be moved to the left.

The fabric rollers may also be raised and lowered by moving either pull rod longitudinally, which will cause a simultaneous parallel movement of all the bell crank levers, for instance if the pull-rod 20 is moved to the right by a downward movement of the rod 22 all of the free ends of the bell-crank levers will move upward and by means of the flanges 12, 13 will cause the roll-supports 9 to 11 to simultaneously move upward. By imparting an upward or downward movement to the rod 31 the double-armed levers 32 are rocked and the tie-rods 26—27, which engage the supports 9—11 by the rollers 28 will move said tie-rods longitudinally and impart a simultaneous lateral movement to said supports and move the fabric rolls longitudinally. By moving both

the rods 22 and 31 at the same time, both a lateral and longitudinal movement will be imparted simultaneously to the fabric rolls.

It is immaterial what means are used to 5 actuate the rods, 22 and 31.

I claim:

1. In an embroidery machine, a plurality of fabric rolls, independent end uprights supporting said rolls, independent intermediate uprights supporting the latter, and mechanism connected to each upright to guide and to impart simultaneously to said uprights, simultaneous and independent longitudinal and transverse movements.
- 10 2. In an embroidery machine, a plurality of fabric rolls, independent end uprights supporting said rolls, independent intermediate uprights supporting the latter, a lever for each support relatively movable thereto, means to actuate said levers simultaneously to raise and lower the supports and means to move the supports laterally.
- 15 3. In an embroidery machine, a plurality of fabric rolls, independent end uprights supporting said rolls, independent intermediate uprights supporting the latter, a plurality of pivotally connected levers each movably connected to a support, means to actuate said levers simultaneously to raise 20 or lower the supports, and means to move
- 25
- 30

the latter transversely independently of the actuation of the levers.

4. In an embroidery machine, a plurality of fabric rolls, independent end uprights supporting said rolls, independent intermediate uprights supporting the latter, a plurality of pivotally connected levers each movably connected to a support, means to actuate said levers simultaneously to raise or lower the supports, and means to move 40 the latter transversely, simultaneously with the raising and lowering of the levers.

5. In an embroidery machine, a plurality of fabric rolls, independent uprights supporting the end portions of said rolls, independent uprights supporting the rolls between the end supports, flanges on the supports near both ends thereof, a plurality of pivoted forked members in movable engagement with the flange of the supports, means 45 to simultaneously oscillate the forked members, and means to move the supports relatively to the forked members.

In testimony whereof I affix my signature in presence of two witnesses.

HANS HARDEGGER.
